UNITED STATES PATENT OFFICE

CHARLES W. POTTER, OF WALTHAM, MASSACHUSETTS, ASSIGNOR TO ATLANTIC REGISTER COMPANY, OF BOSTON, MASSACHUSETTS, A CORPORATION OF MASSACHUSETTS

FILING REGISTER

Application filed April 8, 1929. Serial No. 353,320.

This invention relates to a filing register adapted for holding accounts, sales slips or other commercial papers in a systematic arrangement for affording quick and easy access thereto and relates more particularly to that type of filing register comprising a series of leaves hinged together and each provided with one or more spaces or pockets.

The principal object of the invention is the provision of a filing register of the character described which is simple in construction and operation having few parts and affording ready and convenient access to its contents.

Another object of the invention is the provision of a structure in which the filing leaves, hinged together in a series, may be treated as a unit and when not in use stored in a safe or other suitable depository or, when being used, may be easily connected to suitable supports in a frame for permitting easy manipulation for inspection and filing of records.

Another object of the invention is the provision of a register in which the leaves may be turned over with little or no effort and in which the exposed faces of the leaves are always at the same level irrespective of the position of the exposed leaves in the series thereby facilitating and making more convenient the inspecting and filing of records.

A further object is the provision of a structure which permits expansion of the register by the addition of leaves whenever required.

An additional object is the provision of a leaf built up to any desired size from a plurality of filing units which may be stamped out of sheet-metal and easily assembled with in a band or frame.

Other objects of the invention will be more specifically set forth and described hereinafter.

My invention contemplates a filing register comprising a plurality of filing leaves hinged together on one side in a series and a suitable frame carrying two supports mounted for movement in synchronism along intersecting paths but in opposite directions in relation to the point of intersection of

said paths. When in use the two end leaves of said series are detachably secured one to each of said supports which breaks the series of filing leaves into two hingedly connected tiers with one face of the top leaf of each tier exposed to view. The turning of the leaf from one tier to the other exposes the other face of the leaf turned and at the same time causes the tier from which the leaf is turned to move a corresponding distance toward the point of intersection of the paths of movement and the other tier to move the same distance away from said point. The result is that the exposed faces of the top leaves of the two tiers are always at the same level.

When the register is not in use or at the close of business each day the series of filing leaves may be disconnected from the two supports and folded together into a single stack and placed in a safe or other suitable depository.

Referring to the drawings illustrating one embodiment of the invention, Figure 1 is a view in perspective of a filing register constructed and adapted to be operated in accordance with my invention, Fig. 2 is an end elevation of the same showing all of the leaves, with the exception of one end leaf, on one side of the frame; Fig. 3 is a similar view showing all the leaves, with the exception of the other end leaf, on the other side of the frame; Fig. 4 is a view in perspective of portions of a plurality of units combined to form a leaf; Fig. 5 is a sectional view on line 5—5 in Figure 3 looking upwardly of the means for locking an end leaf into one of the leaf supports with the locking means shown in solid lines in locked position and in broken lines in unlocked position; Fig. 6 is a vertical sectional view on line 6—6 in Fig. 2; and Fig. 7 is a transverse sectional view on line 7—7 in Fig. 5.

Referring to the illustrated embodiment of the invention, there is shown a plurality of leaves 10 hinged together on one side, to form a series, by hinges 12. Each leaf is hinged to the two adjacent leaves one on each side with the exception of the two end leaves which are each hinged to one leaf.

The leaves may be made in any suitable manner and one form of construction is shown in which each leaf is preferably built up of a number of filing units 14 enclosed 5 within a band or frame 16 (Figs. 4 and 7), each of which units consists of a plate having side flanges 18 and end flanges 20 all turned at right angles to the body of the unit. The side flanges are turned in one direction and then reversed so as to interlock with similarly formed flanges on reversed adjacent units to permit the building up of 10 a leaf 10 from a number of units. Preferably the two end flanges on each unit are turned in opposite directions for centering the plates in the band 16 but this is not absolutely necessary and if desired they may both be turned in the same direction. The units are held within the enclosing band in 15 any suitable manner such, for instance, as by spot welding at points 22 and the two ends of the band 16 may be lapped and secured together by rivets 24. The band is of sufficient width to afford filing spaces or 20 pockets on each face of the leaf corresponding in number to the number of units making up the leaf and in each pocket is pivotally mounted a clip 26 of any suitable form held by a spring 28 against the body of the 25 unit for holding in place the papers filed thereunder, (Fig. 1).

For hinging the leaves together in a series, each leaf is provided on its rear side with a pair of straps 30, each strap having 30 at each end a pair of lateral extensions 32 which are bent about the band 16 to hold the strap thereon (Figs. 1 and 6). The straps on the intermediate leaves are provided on each side with two separated hinged 35 knuckles arranged off-center with respect to the longitudinal axis of the strap so that straps on adjacent leaves may be reversed to secure a staggered arrangement and thereby permit a closer formation of the 40 leaves in the stack. The straps on the two end leaves have knuckles on only one side and when the knuckles on adjacent straps are interlocked and pins are inserted the stack of leaves is then hinged together in a 45 series.

Upon the front edge of each leaf 10 may be mounted a small plate 34 held thereon by having its ends turned about the edges of the bands 16 which plates may be suitably 50 marked either with a letter or with a number to indicate the contents of the leaf and the plates on adjacent leaves are staggered to avoid undue separation of the leaves. Each leaf is shown as provided with two 55 such plates, one adjacent each end which is a preferable number because it prevents the leaves being stacked closer together at one end than the other.

For supporting the stack of filing leaves 60 in operative position for filing records

therein and for the examination of its contents, I provide a frame for carrying two supports mounted for movement in synchronism along intersecting paths but in opposite directions, said supports being adapted 70 to support said stack of filing leaves in two tiers hingedly connected. One form of frame is shown comprising a pair of end frames connected together in fixed separated relation, each end frame resembling the letter A and having two converging legs or standards 36 and 37 connected together near their tops by cross-webs 38 and 39. The two end frames are connected together in 75 separated relation by a rod 40 each end of which is locked in a cross-web 39 between bolts 41 and 42 threaded on the end of the rod and on opposite sides of the web and by a foot piece 44 fastened by screws 45 to the bottom of the two standards 36. 80

The legs or standards 36 and 37 are formed with interior longitudinal passages or run-ways 48 in each of which is slidably mounted a rack-bar 50 and between the two rack-bars in each end frame and meshing therewith is arranged a gear 52 keyed to a shaft 54 rotatably mounted in the two cross-webs 38 and the two rack-bars in each end frame are so arranged in relation to said intermediate gear and to each other that 85 when one is in a lowermost position the other is uppermost (Fig. 3).

The two rack-bars in the two legs 36 constitute a pair for carrying between them a leaf support 56 and the two rack-bars in 90 the other two legs 37 as a pair carry a similar leaf support 58. Each leaf support 56 and 58 has its two ends 60 and 61 respectively of triangular form turned downwardly at right angles and connected to the lower 95 ends of its respective supporting pair of said rack-bars by pins 62. In addition, the two ends 60 of the support 56 are fastened to the rack-bars adjacent the top ends thereof by bolts 64 so that the leaf support 56 is 100 fixed on its pair of rack-bars. The support 58, however, is attached to its respective rack-bars by the pins 62 alone and in consequence, the support is capable of pivotal movement around said pins 62 as centers. 105 To hold the support 58 upwardly, however, there is mounted on each end of the support a helical spring 66 connected at one end to a pin 68 set in the end 61 of the support and at the other end to a pin 70 set in 110 the upper portion of the rack-bar. The two springs 66 tend to draw the support toward the center of the frame but permit it to be moved pivotally in an outward direction when required in the operation 115 of the filing register.

The stack of filing leaves 10 is mounted upon the two supports in two tiers hingedly connected, the two end leaves of the 120 stack being fastened to the two leaf sup- 130

ports. Any suitable means may be provided for fastening the end leaves to the supports but preferably means are provided which permit the end leaves to be detached from said supports when desired in order that the stack may be handled as a unit and placed in a safe or other depository when desired. One form of detachable fastening means is shown in the drawings, particularly Figures 5 and 7, comprising a pair of locking levers 72 mounted on the lower face of each leaf support, the inner ends of said levers being pivotally connected to a link 74 which in turn is pivotally mounted upon a pin 76 centrally located in the leaf support and thereby holds up the inner ends of the levers. Adjacent its locking end each lever 72 is held in position against the bottom face of the leaf support by a screw stud 80 set in the leaf support and nut 81 and the lever is provided with a longitudinal slot 82 which permits longitudinal movement of said lever on said stud. The outer end 84 of each lever is turned upwardly through an opening 86 in the support and then outwardly to engage a slot 88 in the end of the end filing leaf for fastening said leaf to said support. For operating said locking levers, an arm or lever 90 may be formed integral with said link 74 for turning the link on its pivot to throw said levers longitudinally into or out of locking position. In Fig. 5, the levers are shown in full lines in locking position and in broken lines in unlocked position.

For turning the leaves from one tier to the other or vice versa a crank arm 92 may be fixed on one end of the shaft 54 and a screw stop 94 may be set in the gear 52 for engaging the cross web 38 to limit the longitudinal movement of the rack-bars 50.

In the illustrated embodiment of the invention the front legs 36 of the frame are vertical and the rear legs 37 inclined toward the front so that the front tier of filing leaves is movable vertically and the rear tier in an inclined path. The filing leaves on the rear tier are, therefore, turned toward the operator standing in front of the register which facilitates the filing, removal or reading of records on the top face of the top leaf of the rear tier.

The operation of a register constructed in accordance with my invention is extremely simple. Assuming the register to be as shown in Figures 2 or 3 ready for use the filing leaves may be turned over from one tier to the other or vice versa by turning the crank arm 92, and the gears 52 in the direction indicated by the arrow on the gear. If the parts are in the position shown in Fig. 3, the front pair of rack-bars carrying the leaf support 56 will be moved downwardly and the rear pair of rack-bars and leaf support 58 will be moved upwardly which causes the leaves on the rear tier to be turned over in succession upon the front tier so long as the crank arm is turned or until all the filing leaves with the exception of the end leaf which is locked to the support 70 58 have been turned to the front tier when the parts are as shown in Fig. 2. The filing leaves may also be turned by hand, if preferred, and in such case a number of leaves may be turned at the same time in 75 which event the rear leaf support is thrown outwardly somewhat further from the center of the register than when the leaves are turned one at a time.

The rapidity with which leaves may be turned from one tier to the other permits filing or examination of the filed contents of the register to be accomplished with celerity and without any appreciable time being wasted by the laborious turning of 80 leaves slowly one at a time. This is of special advantage if the register is being referred to at frequent intervals.

To remove the stack of filing leaves with their records from the frame for storage in some safe place at the close of business is an operation requiring little time and effort. By throwing laterally the lever 90 on each leaf support, the two end leaves are unlocked and the two tiers may then be 90 folded together into a stack, removed from the frame and placed wherever desired. The stack may with equal expedition be remounted on the frame, broken into two tiers and the end leaves locked to the two supports by merely pushing the levers 90 back into locking position.

In filing records, the papers are merely placed under the clips in the proper filing spaces or pockets and are held therein by 100 the clips.

A filing register constructed in accordance with my invention has many advantages. It is simple and compact in construction and can be made at a low cost and 110 yet is very durable. It is easy to manipulate affording quick access to records filed therein and can be adapted to all kinds of records. It is especially suitable for filing valuable records which require to be stored in a safe outside of business hours. It may be made in various forms and of various capacities to suit different needs. The leaves of the register may be built up of various sized units to accommodate records of different sizes and additional leaves may be added as required or may be removed with little or no effort.

Various forms of frames and various 120 forms of leaves may be employed and the two tiers of filing leaves may be arranged to move in intersecting paths of greater or less divergence than that herein illustrated.

I am not herein claiming the invention of 125

the filing leaf built up of a plurality of filing units as that is the subject of a separate divisional application for United States Letters Patent filed by me December 2nd 5 1932, Serial No. 645,354, for leaf for filing registers.

It is to be understood that my invention is not to be limited to the particular form herein shown and described since it may be embodied in various other forms within the purview of the invention and the scope of the following claims.

What I claim is:

1. A filing register comprising a frame, a 15 pair of supports movable synchronously in opposite directions in said frame, a plurality of filing leaves hinged together on one side in a series, the two end leaves of said series being detachably fastened one to each of 20 said supports and means for imparting said movement to said supports.

2. A filing register comprising a frame, a pair of leaf supports mounted in said frame for synchronous movement in opposite 25 site divergent directions and a plurality of filing leaves hinged together on one side in a series, the two end leaves of said series being detachably fastened one to each of said leaf supports to break said series into two 30 connected tiers and means for moving said supports to turn said leaves from one tier to the other.

3. A filing register comprising a pair of leaf supports and including a pair of rack 35 bars and an intermediate gear means for moving said supports in opposite directions in synchronism, a plurality of filing leaves hinged together on one side in a series, the two end leaves of said series being detachably fastened one to each of said supports to break said series into two connected tiers.

4. A filing register comprising a pair of leaf supports mounted for opposite synchronous movement in relation to the point of 45 intersection of their paths of movement, a plurality of filing leaves hinged together on one side in a series, each of the end leaves of said series being provided with end slots, and means for engaging said slots for detachably fastening the two end leaves of said series one to each of said leaf supports to break said series into two tiers.

5. A filing register comprising a pair of leaf supports mounted for opposite movement in intersecting paths in synchronism, a plurality of filing leaves hinged together on one side in a series, the two end leaves being provided with end slots, and means for engaging said end slots for detachably 55 fastening one of said end leaves to each of said two supports to break said series into two tiers, said leaves being adapted to be turned from one tier to the other for exposing the records filed on said leaves.

6. A filing register comprising a pair of

leaf supports mounted for synchronous movement in opposite directions in intersecting paths, a plurality of filing leaves, each of which is provided with means for holding papers to be filed, said leaves being hinged together on one side in a series, and lever operated means for detachably fastening the two end leaves one to each of said leaf supports for breaking said series into two tiers, said leaves being adapted to be manually turned from one tier to the other to expose their contents.

7. A filing register comprising a pair of supports mounted for movement in intersecting paths, a plurality of filing leaves hinged together in a series, the two end leaves being detachably fastened one to each of said two supports to break said series into two connected tiers and gear means for moving said supports in synchronism in opposite directions relative to the point of intersection of their paths of movements to turn intermediate leaves from one tier to the other.

8. A filing register comprising a pair of supports mounted for movement in intersecting paths, one of said supports being also mounted for pivotal movement, a plurality of filing leaves hinged together on one side in a series, the two end leaves being detachably connected one to each of said two supports for supporting said leaves in two tiers and means whenever a leaf is turned from one tier to the other for moving said supports in opposite directions in relation to said point of intersection to maintain the tops of said tiers at the same level.

9. A filing register comprising a pair of supports, rack and gear means for moving said supports in intersecting paths in synchronism but in opposite directions, a plurality of filing leaves hinged together on one side in a series and carried by said supports in two tiers hinged together and a pair of locking levers mounted on each support for locking thereto one end leaf of said series.

10. A filing register comprising a frame, a pair of supports, a plurality of filing leaves hinged together in series and supported by said supports in two tiers hinged together, the two end leaves of said series being fastened one to each of said supports, a pair of rack-bars, one on each of said supports, an intermediate gear meshing with both said rack-bars and means for turning said gear to move said rack-bars and said supports in opposite directions to turn said leaves from one tier to the other.

11. A filing register having, in combination, a frame, two pairs of rack-bars mounted in said frame for longitudinal movement, a pair of leaf supports, each carried by one of said pairs of rack-bars, a plurality of filing leaves hinged together in series and

- carried by said supports in two tiers hinged-
ly connected and means for moving said
pairs of rack-bars in synchronism but in op-
posite directions to turn said filing leaves
6 from one tier to the other or vice versa.
12. A filing register having, in combina-
tion, a frame having two pairs of guideways
one in front and one in the rear, two pairs
10 of rack-bars mounted in said guideways for
longitudinal movement therein, a pair of
leaf supports, each carried by one of said
pairs of rack-bars, a plurality of filing leaves
15 hinged together in series and carried by
said supports in two tiers hingedly connect-
ed and means for moving said pairs of rack-
bars in synchronism but in opposite direc-
tions to turn said filing leaves from one tier
to the other or vice versa.
13. An account register comprising two
20 end frames connected together in spaced rela-
tion, a pair of guideways in each end
frame, said guideways converging together
at their upper ends, a rack-bar slidably
mounted in each of said guideways, a pair
25 of leaf supports, each of said leaf supports
being pivotally mounted on and between two
of said rack-bars one in each frame, gear
connections between the rack-bars of each
pair so arranged that the movement of one
30 rack-bar causes a corresponding movement
in the other rack-bar in an opposite direc-
tion and a series of filing leaves hinged to-
gether on one side, the two end leaves being
fastened one to each of said two sup-
35 ports to break said series into two tiers.
14. A filing register comprising a pair of
leaf supports, means for moving said sup-
ports in intersecting paths but in opposite
directions in synchronism, a plurality of
40 filing leaves hinged together on one side in
a series and a pair of locking levers mounted
on each support for locking thereto one end
leaf of said series.
15. A filing register comprising a pair of
45 supports, rack and gear means for moving
said supports in intersecting paths in syn-
chronism but in opposite directions, a plu-
rality of filing leaves hinged together on one
50 side in a series and mounted on said sup-
ports in two tiers hinged together, a pair of
locking levers mounted on each support for
locking thereto one end leaf of said series
and a lever for operating said locking levers
55 simultaneously.
16. A filing register comprising a frame, a
pair of members mounted in said frame for
synchronous movement in intersecting paths
but in opposite directions, a support mounted
60 on each of said members, one of said
supports being fixed to its respective member
and the other of said supports being pivot-
ally mounted on its member, a spring for
holding said pivotally mounted support in
65 operative position on its member, a plu-
rality of filing leaves hinged together on
one side in a series and mounted on said sup-
ports in two tiers hinged together and means
for locking each end leaf to one of said
70 supports.
17. A filing register comprising a frame, 70
a pair of members mounted in said frame
for synchronous movement in intersecting
paths but in opposite directions, a support
mounted on each of said members, one of
75 said supports being fixed to its respective
member and the other of said supports be-
ing pivotally mounted on its member, a
spring for holding said pivotally mounted
support in operative position on its member,
80 a plurality of filing leaves hinged together
on one side in a series and mounted on said
supports in two tiers hinged together and
means for locking each end leaf to one of
85 said supports; said means comprising a pair
of locking levers mounted on each support
and a lever for operating said locking levers.
18. A filing register comprising a pair of
90 supports, a plurality of filing leaves hinged
together on one side in a series, the two end
leaves of said series being fastened one to
each of said supports to break said series
into two tiers, and means for moving said
95 supports in opposite directions to turn leaves
from one tier to the other.
19. A filing register comprising a pair of
100 supports, a plurality of filing leaves hinged
together on one side in a series, the two end
leaves of said series being fastened one to
each of said supports to break said series
into two tiers, and means for moving said
105 supports in opposite directions in intersect-
ing paths to turn leaves from one tier to the
other.
20. A filing register comprising a pair of
leaf supports mounted for synchronous
110 movement in opposite directions in intersect-
ing paths, a plurality of filing leaves hinged
together on one side in a series, the two end
leaves of said series being detachably fast-
ened one to each of said leaf supports to
115 break said series into two connected tiers
and crank operated means for moving said
supports to turn said leaves from one tier to
the other.
21. A filing register comprising a frame,
120 a pair of rack bars mounted on said frame
for longitudinal movement, a gear interme-
diate said rack bars for moving them in op-
posite directions, a leaf support fixedly
mounted on one of said rack bars, another
leaf support pivotally mounted on the other
125 of said rack bars and a plurality of filing
leaves fastened together on one side in a
series, the two end leaves being detachably
fastened one to each of said two supports to
break said series into two tiers.
- In witness whereof, I hereunto set my
hand this fourth day of April, 1929.
- CHARLES W. POTTER. 130
